CLAIM

The ornamental design for a mobile phone, as shown and described.

DESCRIPTION

FIG. 1 is a front-right side perspective view of a mobile phone showing our new design;

FIG. 2 is a rear-right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in FIGS. 2, 3, 4, 7, and 8 illustrate portions of the mobile phone that form no part of the claimed design.

1 Claim, 7 Drawing Sheets
